UNITED STATES PATENT OFFICE.

WESLEY THOMAS SMITH, OF RANGER, TEXAS.

MUFFLER.

Application filed March 16, 1925. Serial No. 15,835.

The invention relates to mufflers for internal combustion engines, preferably of the stationary type, and has for its object to provide a device of this character which will eliminate back pressure in the engine, produce a silent exhaust, prevent back pressure, and consequently reduce the fouling of the spark plugs to a minimum, as well as the wear on the pistons and piston ring, and at the same time produces enough heat in the muffler to dry all moisture in the exhaust gases if water is allowed to get in the cylinder.

A further object is to provide an exhaust muffler for stationary internal combustion engines, which muffler is vertically disposed, and comprises a chambered casing preferably embedded in the ground, and connected to the engine exhaust pipe. The chambered casing is provided with an upwardly extending cylindrical casing having a plurality of compartments therein formed by horizontally disposed partitions, which partitions are provided with a plurality of registering gas passages of the same diameter as the interior diameter of the exhaust pipe, thereby preventing a choking action of the gases without back pressure thereon, and allowing the gases to expand in the various chambers in its passage through the muffler.

A further object is to provide the upper end of the casing with a reduced angularly disposed pipe having an interior diameter substantially the same as the gas passages through the partitions, and which angularly disposed pipe discharges the gases into the atmosphere after they have passed through the various expansion chambers.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:—

Figure 1 is a side elevation of the muffler. Figure 2 is a vertical longitudinal sectional view through the muffler.

Referring to the drawing, the numeral 1 designates exhaust pipe of an internal combustion engine of a stationary type, and which exhaust pipe is preferably imbedded in the ground 2, and has its end provided

with a flange 3, which is secured to the flange 4 of the horizontally disposed pipe 5. The pipe 5 is carried by a vertically disposed casing 6 having a gas expansion chamber 7 therein, and into which gas is discharged from the exhaust pipe and allowed to expand, without creating a back pressure on the engine. Extending vertically from the upper end of the cylindrical casing 2 is a reduced cylindrical casing 8, and which casing 8 is divided into a plurality of expansion chambers 9 by means of horizontally disposed partitions 10 having gas passages 11 therethrough. Therefore it will be seen that the gases in passing through the muffler expand many times before passing therethrough. Consequently the noise of the explosions is muffled. Gas passages 11 are of the same diameter as the interior diameter 75 of the exhaust pipe 1, and the horizontally disposed pipe 5. Therefore it will be seen that a choking operation will not take place which causes back pressure in the engine, and which choking action causes the formation of carbon and fouling of the spark plugs as well as considerable wear on the pistons and piston rings, all of which difficulties are obviated by the present device. The muffler produces sufficient heat therein 80 to dry all moisture in the exhaust gases if water is allowed to get in cylinders of the engine. Therefore water will not be discharged from the device. The upper end of the casing 8 is provided with an angularly disposed discharge pipe 12, the inner diameter of which is substantially the same as the upper gas passage 11. Therefore it will be seen that after the final expansion of the gases, it will not be restricted and will be 85 discharged to the atmosphere angularly. It will be noted that the pipe 12 by being angularly disposed prevents entrance of water into the muffler when raining. Therefore the danger of water entering the engine 130 through the exhaust pipe is obviated and at the same time the end of the muffler as a whole is disposed a substantial distance above the ground 2 where injury to a person incident to the discharge of the gases will 135 be obviated, as the device is preferably in the neighborhood of seven feet high.

From the above it will be seen that a muffler is provided for internal combustion engines, which is simple in construction, 110 positive in operation and one which may be cheaply manufactured and sold.

The invention having been set forth what is claimed as new and useful is:—

A muffler for internal combustion engines, said muffler comprising a cylindrical casing, vertically disposed and adapted to be imbedded in the ground, a right-angularly disposed intake pipe carried by said cylindrical casing, a reduced vertically disposed casing carried by the upper end of the cylindrical casing, said vertically disposed casing being divided into a plurality of expansion cham-

bers by means of horizontally disposed partitions having gas passages therethrough and a discharge pipe carried by the upper end of the vertically disposed casing and of substantially the same interior diameter as the diameter of the gas passages through the partition and the interior diameter of the intake pipe.

In testimony whereof I have signed my name to this specification.

WESLEY THOMAS SMITH.
